Inventor:

Karel Lobosicky

UNITED STATES PATENT OFFICE

KAREL LOBOSICKÝ, OF PRAGUE, CZECHOSLOVAKIA

APPARATUS FOR FINGER GYMNASTICS

Application filed August 20, 1928, Serial No. 300,848, and in Czechoslovakia August 24, 1927.

This invention relates to a device such as used by instrumental musicians for exercising the wrist and the fingers and of the kind comprising a plurality of finger rings connected by means of elastic strings to a support, and the invention consists in the provision of a support in the form of a hooked standard which is held adjustably in a felt-lined bracket adapted to be secured to the head of a violin or the like so as to allow the fingers to be exercised in their natural positions over the finger board.

Figs. 1 and 2 of the accompanying drawings represent views at right angles of a device adapted for connection to a violin or the like.

Fig. 3 is a bottom view of the fastening clamps, and

Fig. 4, a view on a reduced scale showing the device mounted for use.

The device shown in the drawings comprises a clamp 1 which is provided with a felt or like lining 3 and adapted to be secured by means of a clamping screw 2 to the head of a violin or similar stringed musical instrument. The clamp has a bore 4 for the reception of a standard in the form of a stout wire 5 adapted to be adjusted longitudinally in the clamp and to be secured thereto in various positions by means of a set-screw 9. The upper end of the standard is formed with a hook 6 from which a plurality of finger rings 8 is suspended by means of elastic strings 7 composed of rubber or wire coils. The standard is preferably bent so that, with the clamp between the tuning pegs, as shown in Fig. 4, the upper part of the standard leans towards the finger board. The instrument is held in the usual way, and the fingers are inserted in the rings 8 and exercised together with the wrist in opposition to the elastic strings.

The device is not only useful for beginners for strengthening the wrist and finger muscles, but also for expert players, in that an occasional use of the device, particularly before a performance, will tend to put the muscles into proper working condition.

I claim:—

1. A device for exercising the wrist and

fingers of instrumental musicians, comprising a felt-lined screw clamp attachable to the head of an instrument of the violin type, a standard held adjustably in said clamp, a plurality of finger rings, and elastic strings whereby said rings are suspended from the standard. 55

2. A device as claimed in claim 1 wherein the standard has the form of a stout wire having at one end a hook to receive the elastic strings. 60
